UNITED STATES PATENT OFFICE.

JESSIE R. McLAREN, OF MASSENA, IOWA.

LOCKET.

1,377,902.

Specification of Letters Patent. Patented May 10, 1921.

Application filed December 18, 1918. Serial No. 267,825.

To all whom it may concern:

Be it known that I, JESSIE R. McLAREN, a citizen of the United States, residing at Massena, in the county of Cass and State 5 of Iowa, have invented certain new and useful Improvements in Lockets; and I do hereby declare the following to be a full, clear, and exact description of the invention, such as will enable others skilled in the 10 art to which it appertains to make and use the same.

This invention relates to ornaments and the primary object of the invention is to provide an improved device, for attaching 15 soldiers' buttons or the like to articles of jewelry, whereby the same can be readily carried around and shown. It is a well known fact that girls generally collect or wear soldiers' buttons, and this invention 20 has for one of its objects to provide means for securing the button to articles of jewelry, whereby the same may be readily worn.

Another object of the invention is to provide an improved means for securing the 25 button or the like to a locket.

A further object of the invention is to provide an improved device of the above character, which is durable and efficient in use, one that is simple and easy to manufacture, and one that can be placed upon 30 the market at a reasonable cost.

With these and other objects in view, the invention consists in the novel construction, arrangement and formation of parts, as will 35 be hereinafter more specifically described, claimed and illustrated in the accompanying drawings, forming a part thereof, in which:

Figure 1 is a front view of the improved locking showing the same open.

Fig. 2 is a rear view of the locket showing the same open.

Fig. 3 is a front view of the locket showing a button attached thereto.

Fig. 4 is a side elevation of the improved 45 locket.

Referring to the drawings in detail, wherein similar reference characters designate corresponding parts throughout the several views, the numeral 1 generally indicates 50 the improved locket which includes front and rear sections 2 and 3, hingedly connect-

ed together as at 4. The section 3 is arranged for receiving a photograph or the like, which is adapted to be held in place by the ordinary ring or retaining device 5. 55 The section 2 may also be arranged for receiving a photograph or the owner's name or initials may be engraved upon the same as shown at 6. The front section 2 of the locket 1 is adapted to carry outwardly extending spaced bendable triangular shaped tongues 7 which are adapted to retain the army button 8 in position.

In use, when it is desired to place the button upon the locket, the loop (not shown) 65 by means of which the button is normally fastened to the garment is either broken off or bent flat against the back of the button and the same is laid upon the outer face of the section 2 of the locket and the tongues 70 are then bent over into engagement with the button which effectually holds the same against displacement. It is to be understood that any type of button bearing the insignia of the corps to which the owner 75 of the button may belong may be attached to the locket.

A loop 9 has its terminals secured as at 10 to rear section 3 of the locket and forms means, whereby the locket may be placed 80 upon a ribbon 11 and thus worn as a bracelet or the like.

It is to be understood that the locket can be made of any preferred material and the tongues can be, if so desired, made of bronze 85 or some other material resembling the color of the button.

In practice, I have found that the form of my invention illustrated in the accompanying drawings and referred to in the 90 above description, as the preferred embodiment, is the most efficient and practical; yet realizing the conditions concurrent with the adoption of my device will necessarily vary, I desire to emphasize that various minor 95 changes in details of construction, proportion and arrangement of parts may be resorted to, when required without sacrificing any of the advantages of my invention as set forth.

What I claim as new is:

A locket comprising front and rear cir-

2
circular sections, a hinge connecting said sections, a catch for detachably connecting the sections, means for securing a photograph in the rear section, triangular shaped 5 tongues formed on the periphery of the front section and adapted to be bent to overlie the front face thereof for retaining an ornamental element thereon, and a loop

formed on the outer face of the rear section to receive the belt worn by a person.

10

In testimony whereof I affix my signature in presence of two witnesses.

JESSIE R. McLAREN.

Witnesses:

H. E. PHIPPS,
MAE McLAREN.
